UNITED STATES PATENT OFFICE.

VIRGIL McCLELLAN, OF LAWSON, AND GOVERNOR D. WARREN, OF VILLA PARK, COLORADO.

RAILWAY-FROG.

SPECIFICATION forming part of Letters Patent No. 556,685, dated March 17, 1896.

Application filed May 11, 1895. Serial No. 549,008. (No model.)

To all whom it may concern:

Be it known that we, VIRGIL McCLELLAN, of Lawson, in the county of Clear Creek, and GOVERNOR D. WARREN, of Villa Park, in the county of Arapahoe, State of Colorado, have invented certain new and useful Improvements in Railway-Frogs; and we do hereby declare the following to be a full, clear, and exact description of the invention, such as will enable others skilled in the art to which it pertains to make and use it, reference being had to the accompanying drawings, which form part of this specification.

Our invention relates to improvements in railway-frogs, and the object of the same is to provide a movable rail-frog which is so adjusted by the switch-throwing mechanism as to make a continuous rail for the switch when open, and for the main track when the switch is closed.

With this object in view our invention consists in the novel features of construction hereinafter fully described and claimed, and illustrated in the drawings, in which—

Figure 1 is a plan view of a section of a main track and siding, showing the switch provided with our improved frog. Fig. 2 is an enlarged detail view showing the frog-operating mechanism.

A is the main track; B, the siding; C, the movable rail at the intersection thereof, and D the base-plate upon which the rail turns.

E are the movable switch-rails, and F the transverse longitudinally-movable bar for opening and closing the switch.

Upon cross-tie G, adjacent to which bar F is arranged, is mounted the casing H, in which are pivotally secured the segment-levers I I'. These segments are so arranged that their peripheries move quite adjacent to each other, and each is connected to bar F by a link J.

K is a chain or rod secured to the periphery of lever I and extending to and secured on the rounded side of the bell-crank lever L, to the inner end of which movable rail C is connected by link M. This connection is to the end of the said movable rail nearest the switch, while the opposite end is connected by a similar lever m and chain or rod O to the segment-lever I'. Thus when the switch is opened, as shown in the drawings, lever I',

rod O, and bell-crank lever N have thrown the movable rail in line with the inner siding-rail so as to make a continuous track over the frog, while when the switch is closed the reverse longitudinal movement of bar F will turn backward lever I, drawing forward chain K, which causes bell-crank lever L to move the pivoted frog in line with the main track, thus making a continuous passage thereon over the frog, as will be understood. The rods or chains leading from the switch to the frog are suitably incased in a tube-casing P, while the longitudinal sides of base B are formed with a passage to accommodate the same, as shown.

The switch-throwing bar may be operated by any desired mechanism, none being here shown, as it forms no part of our invention.

By means of the arrangement here shown it will be seen that the frog coacts exactly with the movement of the switch-throwing bar, and as compensating springs Q are arranged in the chains or rods connecting the levers a tension is exerted on the latter which causes them to hold the rail tightly in either position it may be thrown.

Having thus fully described our invention, what we claim, and desire to secure by Letters Patent, is—

1. The combination of the pivoted frog, the bell-crank levers having rounded outer arms, the links connecting the inner arms to the frog on opposite sides of its pivot, and the operating-lines extended over the rounded surfaces of the lever-arms and secured thereto, substantially as shown and described.

2. The combination of segments I, I', a means for turning them, the operating-lines extended around and secured to the outer peripheries of said segments, and the movable frog adapted to be adjusted by the lines, substantially as shown and described.

3. The combination of the segments I, I', arranged with their peripheries adjacent each other, the operating-lines extended around and secured to said peripheries, the operating-bar, links J pivoted to the bar and extended therefrom in like direction and pivotally secured at their outer ends to the segments, whereby when the operating-bar is moved the segments will be turned in opposite direc-

tions and a corresponding movement given the lines, and the frog and operating mechanism adapted to be actuated by the lines when thus moved, substantially as shown and described.

- 5 4. The combination of the segments arranged with their peripheries adjacent each other, an operating mechanism secured to an extremity of each segment, the lines extended around the segments and secured thereto at the point of connection of the operating mechanism, whereby when one line is drawn upon by the turning of its segment the other will be loosened and vice versa, and the frog, and operating mechanism actuated by said lines, substantially as shown and described.
- 10
- 15

5. The combination of the movable frog, the switch-throwing mechanism, the lines arranged therebetween for operating the frog, base D provided with the longitudinal casing 20 upon one side, and the covering extending from said casing to the switch-throwing mechanism, said covering inclosing the operating lines, substantially as shown and described.

In testimony whereof we affix our signatures in presence of two witnesses.

VIRGIL McCLELLAN.
GOVERNOR D. WARREN.
